Inventor:

John Stolpe,
by S. W. Anderson for
Attorneys

UNITED STATES PATENT OFFICE.

JOHN STOLPE, OF MCPHERSON, KANSAS.

MOTOR-WHEEL.

1,301,881.

Specification of Letters Patent. Patented Apr. 29, 1919.

Application filed August 14, 1918. Serial No. 249,561.

To all whom it may concern:

Be it known that I, JOHN STOLPE, a subject of the King of Sweden, resident of McPherson, in the county of McPherson and State of Kansas, have made a certain new and useful Invention in Motor-Wheels; and I declare the following to be a full, clear, and exact description of the same, such as will enable others skilled in the art to which it appertains to make and use the invention, reference being had to the accompanying drawings, and to letters or figures of reference marked thereon, which form a part of this specification.

15 Figure 1 is a side view of the invention. Fig. 2 is a detail face view of the wheel.

The invention has relation to wind motors, and it consists in the novel construction and combinations of parts as hereinafter set forth.

In the accompanying drawings illustrating the invention, the numeral 2, designates a supporting frame, wherein are journalcd the upper and lower ends of a rotary shaft 3, 25 said shaft carrying inner and outer concentric semi-circular hangers 4 and 5, the ends of which respectively loosely engage the said shaft, resting upon fast collars 6 of the latter.

30 A horizontal power shaft 7 is loosely journaled at 8 and 9 in intermediate or central portions of the respective hangers, and mounted thereupon between the two hangers or in the space or interval intervening, 35 is a stationary cylindrical casing 10, loose upon the shaft, and at diametric portions of its forward circumferential edge suitably clamped or secured at 1 to the portions of the outer hanger intermediate or midway 40 between its center and its ends.

The forward half of the casing is provided with a radial series of vanes or blades 12, each vane preferably substantially rectangular and flat, and being disposed obliquely or inclined with relation to the casing and to the hub portion 13 of the latter, the vanes being rigidly secured at their inner and outer ends to the casing and to its hub portion.

45 Working within the rear half of the casing is the motor wheel 14, made up of an

outer cylindrical shell 15, a hub portion 16, and a radial series of vanes or blades 17, the latter also preferably flat and rectangular and secured at their respective inner and outer ends to the said shell and hub portion. The radial blades of the motor wheel are inclined or oblique with respect to the shell and hub of the said wheel and are inclined oppositely to the vanes or blades of the stationary casing, so that the latter being presented to or facing the wind, the direction of the wind will be changed accordingly and will impinge and act upon the inclined vanes of the motor wheel proper at about right angles thereto, this being the most effective angle.

The plane of the forward face of the casing is arranged chordwise with respect to the outer hanger, and the plane of the rear face of the motor wheel proper is arranged tangent-wise to the inner hanger, the casing and wheel proper being well supported and braced by these two hangers.

The invention is designed preferably to 75 be suitably mounted upon an air ship, for driving a dynamo or other engine. The invention is also capable of use as a wind wheel having a vane suitably proportioned to present the stationary casing 10 and its 80 vanes to the wind, and in this latter case, the hangers 4 and 5 will be capable of pivotal movement upon the vertical shaft 3.

I claim:

A motor wheel, comprising a vertical shaft at its upper and lower ends suitably journalcd in a supporting frame, and having fast collars, forwardly projecting inner and outer concentric semi-circular hangers having their rear ends loosely engaging said shaft and resting upon the collars thereof, a transverse or horizontal shaft loosely journaled in the central portions of said hangers and having a bevel-gear driving connection with said vertical shaft, a stationary cylindrical casing located in the interval between the inner and outer hangers the forward circumferential edge of said casing at diametrically opposite points rigidly secured to the outer hanger, the forward half of said casing 100 having a radial series of inclined vanes, and a rotary wheel or motor wheel proper working

within the rear half of said casing and having also a radial series of vanes inclined with respect to the shell and hub thereof and inclined oppositely with respect to the stationary vanes of said casing, said vertical shaft having a driving connection with a dynamo or other engine.

In testimony whereof I affix my signature, in presence of two witnesses.

JOHN STOLPE.

Witnesses.

O. L. M. KRELL,
CLIFFORD NELSON.
